UNITED STATES PATENT OFFICE.

CHARLES E. ADAIR, OF BUFFALO, NEW YORK.

HOVER.

1,204,836.

Specification of Letters Patent. Patented Nov. 14, 1916.

Application filed January 6, 1916. Serial No. 70,600.

To all whom it may concern:

Be it known that I, CHARLES E. ADAIR, a citizen of the United States of America, and a resident of the city of Buffalo, county of Erie, and State of New York, have invented 5 certain new and useful Improvements in Hovers, of which the following is a full, clear, and exact description.

My invention relates generally to hovers 10 for chickens and other fowl or birds, and more particularly to brooders for little chicks hatched in incubators.

The principal object of my invention is to provide a colony hover, which may be employed 15 to take care of and successfully protect a large number of chicks in a room or colony house.

My device provides temperature controlling means, whereby the temperature may be 20 automatically maintained at any desired and regulatable point. Moreover, my device is cheap to manufacture; economical in fuel consumption and simple and easy to operate.

The above objects and advantages have 25 been accomplished by the device shown in the accompanying drawings.

In the drawings: Figure 1 is a sectional elevation through the center of my hover. Fig. 2 is a fragmentary, sectional elevation 30 of my device, showing the damper and the upper part of the control therefor. Fig. 3 is a fragmentary elevation showing the lower part of the damper controlling means. Fig. 4 is a fragmentary elevation showing 35 the lower part of a modified form of damper controlling means. Fig. 5 is a fragmentary, sectional elevation of a modified form of damper arrangement.

In the drawings, 5 represents the stove 40 of my device, which is preferably arranged for burning coal.

6 is the upper part of the combustion chamber of the stove, and 7 is the lower part thereof. These parts are preferably frusto-conical in form and are united at their largest diameters near the center of the combustion chamber by a flange connection 8. Beneath the fire pot is arranged the ash pit 9 of the stove, which is provided with a detachable door 51. This ash pit sets upon a base 10, which has its lower edge raised above the floor and is provided with a plurality of feet 11. The base 10 is partly filled with asbestos 12, and beneath this asbestos is placed a bottom 13. The parts of the stove are held together by stay-bolts 14,

which pass through the flange 8, down through the ash pit and through the bottom 13, thus securely holding the parts together.

15 are the grates of my stove, beneath which is arranged a suitable ash pan.

Around the stove is disposed a flaring canopy 16, at the outer rim of which is preferably arranged a downwardly extending wall 17. The canopy is provided with a 65 central aperture which slips over the canopy flange 18. This flange is arranged to set upon the edge of the upper part 6 of the combustion chamber and is provided with a suitable bail 19 by which the canopy may 70 be raised from the stove by a rope 20, passing over suitable pulleys 21, and thus be elevated while cleaning about the heater.

The upper part 6 of the combustion chamber is provided with a suitable charging hole 75 22, having a cover 23 fitted thereto. A sleeve 24 is also provided, over which is fitted the smoke or draft pipe 25. A draft opening 26 is also provided in the upper 80 wall of the part 6. A damper chamber 27 is formed within the upper part of the part 6 by a damper box 28 secured against the side and upper walls of this part of the combustion chamber. This damper box extends over the area covered by the sleeve 24 and the draft opening 26, and is provided in its lower wall with an opening 29, which registers with the opening 26 in the top of the part 6. The damper 30 of my device is disposed within the damper chamber, between 85 the openings 26 and 29, and arranged to open or close either of said openings. A rod 31 passes through the damper 30 and is provided with a hook or an eye at its upper end and connected with this hook is a damper 90 lever 32, which is supported by means of a knife edge 33 resting upon a supporting member 34 carried on the upper face of the part 6. Connected with the outer end of the damper lever is a damper rod 35, which extends down the outside of the combustion chamber and is connected at its lower end with the thermostat controlling means.

The thermostat controlling means comprises a disk thermostat 36 arranged beneath a suitable flange 37, carried by a thermostat arm 38. The arm 38 is preferably carried by the ash pit 9 of the heater and is preferably provided with an aperture 39 near its inner end through which the 100 damper rod is arranged to pass.

40 is a thermostat lever which is arranged

beneath the thermostat arm 38 and supported by means of an adjusting bolt 41, which passes through the said lever and thermostat arm 38 and has an adjusting nut 42 at its upper end. The thermostat lever 40 extends out beneath the disk thermostat 36, and its inner end extends inwardly and is connected with the lower hook end of the damper rod 35. At the inner end of this 10 thermostat lever is provided a weight 43, which keeps the outer end thereof constantly in contact with the disk thermostat 36.

In the modification shown in Fig. 4, the 15 thermostat is arranged between the adjusting means and the base portion. In carrying out this form of thermostat, the arm 44 is provided with an offset, central portion 45 and is bent downwardly at its outer end 20 46 and lies in a plane below the inner end thereof. A flange 47 is provided near the outer end for the support of the disk thermostat 36. Arranged above the outer end 46 of the thermostat arm is the thermostat 25 lever 48, which is bent so as to bring its inner, weighted end below the level of the inner end of the thermostat arm 44. The adjusting screw 49 is arranged to pass through the outer ends of the thermostat 30 arm 44 and thermostat lever 48, and is provided with a thumb nut 50, as in the other form.

In the modification shown in Fig. 5, the 35 damper 51 is disposed over the opening 24 in the top of the part 6 and arranged to open and close this opening. The opening 29 in the damper box 28 is also provided in this form of device.

When the form of my device, shown in 40 Figs. 1-4, is to be put into operation, the fire is started and the combustion chamber filled with coal. If the temperature is below the desired point, the damper 30 will be adjusted so that it closes the draft opening 26 in the top of the upper part 6. When 45 in this position, all the draft created through the pipe 25 will draw the air through the fire, opening 29 in the damper box, through the damper box and out of the 50 pipe 25, thus giving the fire the maximum amount of draft and causing it quickly to reach the desired temperature. As the 55 temperature is reaching the predetermined point, the disk thermostat 36 will start to expand and as it does so it will raise the inner end of the thermostat lever. This will cause the damper 30 to be gradually lowered, thus uncovering the opening 26 into the room and tending to close the opening 29 into the fire. If the temperature 60 rises above the predetermined point, the damper 30 will be moved down to a point where it will close the opening 29, thus shutting off the draft from the fire and 65 allowing the heated air from the room to

be drawn in through the opening 26 and up through the pipe 25. Any gases formed in the combustion chamber will pass through the small opening provided in the damper.

In the form of my invention shown in Fig. 5, the damper 51 is down upon the opening 26 when the fire is started thus permitting all of the draft to act upon the fire. When the predetermined temperature has 70 been reached, the damper 51 will be moved upwardly so as to uncover the opening 26. When the opening 26 is partially or wholly uncovered the source of the air going up the smoke pipe 25 will be divided and air will 75 be taken into the damper box 28 through openings 26 and 29. With the opening 26, wholly uncovered, the path of least resistance for the air will be through the opening 26, thereby reducing the draft through 80 the fire and allowing the temperature to fall. The temperature at which the damper 30 will operate may be easily and quickly changed by adjusting the thumb nut of the bolt connecting the thermostat arm and 85 thermostat lever, and the thermostat being arranged near the floor line is controlled by the temperature to which the chicks are 90 exposed.

The frusto-conical form of the parts of 95 the combustion chamber of my stove provides a comparatively large reservoir for coal so that a much desired slow burning fire can be readily controlled therein. Moreover the converging side of the upper 100 part 6 of this chamber reduces the relative size of the flat top portion and the eccentric arrangement of the draft and fuel openings is such that there is no lost space and at the same time no disadvantages caused 105 by the top being reduced in size. Another advantage resulting from my construction is that the heat is radiated from the outer side of the frusto-conical combustion chamber against the flaring canopy and thence 110 deflected upon the chicks. If the heat becomes too great the canopy, being adjustable, can be raised to any desired height above the stove and thus the temperature surrounding the chicks be additionally regulated.

Obviously, some modification of the details herein shown and described may be made without departing from the spirit of my invention or the scope of the appended 115 claims, and I do not wish to be limited to the exact embodiment herein shown and described.

Having thus described my invention, what I claim is:

1. In a stove, the combination of a base portion, a two-part combustion chamber having its greatest diameter near the center, each part thereof being frusto-conical in form, the top of the same being flat and 130

formed with draft and fuel openings eccentrically arranged, a damper in the draft openings, a thermostatic device projecting from the base portion, a vertical damper rod 5 connected thereto, means connecting said damper and said rod, and a canopy supported at the upper part of the combustion chamber and centrally apertured so that the draft and fuel openings are located outside 10 of the canopy.

2. In a hover, the combination of a base portion, a two-part combustion chamber, each part being substantially frusto-conical in form, the two sections being superimposed so that the larger portions of the chamber are connected together, the flat top 15 of the chamber being formed with draft and fuel openings, a damper in the draft opening, a thermostat arm secured to the base, a movable thermostat lever mounted below the arm, means connecting the thermostat lever 20 with the damper, and a canopy supported at the upper part of the chamber and centrally apertured so that the draft and fuel 25 openings are located outside of the canopy.

3. In a hover, the combination of a base portion, an upper stove section above the base having its widest part near the center of the stove and having its sides converging 30 upwardly and downwardly from the center, the flat top of the upper stove section being formed with draft and fuel openings eccentrically arranged, a damper in the draft opening, a thermostatic device projecting from the base portion and a vertical 35 damper rod connected thereto, means connecting said damper and said rod and a vertically-movable canopy supported on the upper part of the upper stove section and 40 centrally apertured so that the draft and

fuel openings are located outside of the canopy.

4. In a hover, the combination of a base portion, a two-part combustion chamber, each part being substantially frusto-conical 45 in form and the chamber having its greatest diameter near the center thereof, the flat top of the same being formed with draft and fuel openings eccentrically arranged, a damper in the draft opening, a thermostatic 50 device projecting from the base portion, a vertical damper rod connected thereto, means connecting said damper and said rod, and a canopy supported at the upper part of the chamber and centrally apertured so 55 that the draft and fuel openings are located outside of the canopy.

5. In a hover, the combination of a base portion, a combustion chamber having its greatest diameter near the center thereof, the 60 sides of the same converging upwardly and downwardly from the center, the top of the chamber being formed with check draft and fuel openings eccentrically arranged, a damper in the draft opening, a canopy sup- 65 ported at the upper part of the combustion chamber and centrally apertured so that the draft and fuel openings are located outside of the canopy, a thermostatic device projecting from the base portion, a vertical 70 damper rod extending upwardly therefrom and means connecting the damper and rod.

In testimony whereof, I have hereunto signed my name in the presence of two subscribing witnesses.
